United States Patent Office

Des. 231,937
Patented June 25, 1974

231,937

CASKET

Edward R. Andrus, Jr., Mount Prospect, Dale E. Fahnestrom, Riverside, and James G. Hansen, La Grange, Ill., assignors to Elder Wilbert Corp., Broadview, Ill.

Filed Mar. 20, 1972, Ser. No. 236,536

Term of patent 14 years

Int. Cl. D31

U.S. Cl. D31—3

FIG. 1 is a top perspective view of a casket embodying our new design;

FIG. 2 is a top plan view of the casket;

FIG. 3 is a side elevational view of the casket;

FIG. 4 is an end elevational view of the casket;

FIG. 5 is an end elevational view of the casket; and

FIG. 6 is a bottom plan view of the casket.

We claim:

The ornamental design for a casket, substantially as shown and described.
